UNITED STATES PATENT OFFICE.

WATSON R. SMITH, OF JACKSON, MICHIGAN.

CUSHION-SPRING.

No. 813,244.

Specification of Letters Patent.

Patented Feb. 20, 1906.

Application filed November 19, 1904. Serial No. 233,546.

To all whom it may concern:

Be it known that I, WATSON R. SMITH, a citizen of the United States, residing in the city of Jackson, in the county of Jackson and State of Michigan, have invented certain new and useful Improvements in Cushion-Springs, of which the following is a specification.

This invention relates to cushion-spring work for couches, beds, chairs, or the like.

One object of the invention is to provide a construction and arrangement wherein the sides of the structure will be straight or at a direct right angle to the top and bottom thereof.

Another object of the invention is to provide a construction and arrangement wherein not only the sides, but the ends, of the structure will be straight or at a direct right angle to the top and bottom thereof, resulting in a perfectly rectangular-shaped construction.

Another object of the invention resides in the provision of an exceedingly simple, inexpensive, light, durable, rigid cushion-work for couch, bed, chair, and similar purposes.

Another object of the invention is to provide an arrangement of a number of convolute or other springs within a wooden frame and associating the springs with a support and peculiarly-shaped stay-wires in such manner that they will be securely connected therewith.

A still further object of the invention is to provide an arrangement and construction of such nature that when pressure is applied to any portion of the cushion it will be distributed over the portion of the cushion surrounding that upon which the pressure is directly applied.

Heretofore when single cone springs have been used in structures of the present character the lower convolution or ends thereof have usually been secured to metallic, wooden, or similar slats in such manner as to permit the wider upper convolutions of the springs to extend out to or over the upper edge of the wooden or like frame to meet the border-wire or the like, so that the sides and ends of the cushion might be formed substantially at a right angle to the top and bottom of the same. I am aware that it is not new, broadly, to arrange springs within a wooden frame and support them therein with the outermost springs out of contact with the frame and the border-wire. I am also aware that single cone springs have been supported within a wooden frame without necessarily

connecting them directly to the frame or to the border-wire associated with a structure of the character herein outlined. I believe, however, that in my construction, wherein the double springs are employed and associated in rows and securely disposed upon corresponding pairs of support-wires, the upper convolutions of each spring of each corresponding row being connected at opposite sides to a peculiarly-formed stay, which latter contacts not only with the opposite sides of the springs, but also at two points with the border-wire, I present a construction and arrangement not heretofore employed and one wherein perfect resiliency and rigidity is manifest.

With these and other objects in view the present invention consists in the combination and arrangement of parts, as will be hereinafter more fully described, shown in the accompanying drawings; and particularly pointed out in the appended claim, it being understood that changes in the form, proportion, size, and minor details may be made within the scope of the claim without departing from the spirit or sacrificing any of the advantages of the present invention.

In the drawings, Figure 1 is a top plan view of a cushion embodying my invention, the wooden frame being removed. Fig. 2 is a bottom plan view of the same, including the wooden frame. Fig. 3 is a transverse sectional view of the invention. Fig. 4 is a top plan view of a portion of a cushion, illustrating the manner in which the end rows of springs are connected to the ends of the border-wire to present a substantially straight end to the cushion. Fig. 5 is a detail perspective view of one of the clips employed for connecting the stays to the springs, and Fig. 6 is a detail perspective view of another form of clip designed to secure the stay to the springs and to the border-wires.

Referring now more particularly to the accompanying drawings, the reference character 1 designates a rectangular or other shaped frame of wood or any other suitable material. Arranged in pairs and disposed within this frame 1 are support-wires 2, the ends of each being bent upwardly, as at 3, and terminating in pointed hooks 4, designed to be driven into the upper edges of the frame 1, the portion 3 of each support-wire lying substantially parallel with the inner face of the frame, with the body portion thereof preferably a little above the line of the under edges

of the frame. By reason of the portions 3 of the support-wires being spaced from the inner face of the frame proper resiliency of the cushion is had when weight is brought to bear thereupon. It will now be understood that the support-wires 2 are arranged transversely of the frame 1, and reference to the accompanying drawings will disclose that upon each pair of support-wires double cone springs 5 are mounted in series. The compression of the springs in the present instance is uniform—that is to say, there is very little, if any, tendency of a tilting of the lower portion of the springs when pressure is brought to bear thereupon, for the reason that the support-wires extend beneath corresponding rows of springs and are secured thereto at opposite edges by means of suitable clips or other elements 6. These clips 6 are made, preferably, of wire, and each is provided at its opposite ends with hooks 7 and an intermediate hook or kink 8, the hooks 7 being clamped, sprung, or otherwise secured around corresponding support-wires and the lower convolution of the corresponding spring, the hook or kink 8 receiving the longitudinal support-wires 9. It should be noted that the kink 8 extends downwardly between the lower convolution of the corresponding spring and the outer face of the corresponding transverse support-wire, the corresponding longitudinal support-wire being clamped, sprung, or otherwise secured into engagement with the kink and disposed below the transverse support-wires, as clearly shown in Fig. 2. While one form of clip has been described for securing the transverse and longitudinal stay-wires and the corresponding springs together, it is to be understood that I do not wish to limit myself to the precise form of clip and that the clips may not necessarily be sprung into engagement with the aforesaid elements, but may be clamped or otherwise secured in connection therewith.

A border-wire 10 is arranged above the frame 1, and the side edges thereof are preferably in alinement with the corresponding outer edges of the wooden frame, the ends of the border-wire terminating in some instance substantially in alinement with the outer edge of the ends of the wooden frame and in other instances not in alinement with the outer edges of the ends of the frame, as will be hereinafter more fully set forth. In any event, however, bridging the border-wire 10 and arranged transversely of the frame 1 is a looped stay-wire or other suitable pressure-distributing element 11, there being one of these elements 11 arranged immediately above each transverse row of springs in the frame, and each is designed to rest upon opposite sides of the upper convolutions and springs. As shown in the drawings, the upper convolutions of the outermost set of springs do not extend beyond the wooden

frame 1, but are confined wholly within the latter. Therefore in order that the border-wire 10 may be associated with the springs in such manner as to permit the same to accompany the springs in their movements the element 11 is extended beyond the outermost springs upon the sides of the cushion and under the border-wire, where a clip 12, different in form from the other clip hereinbefore described, secures the opposite rounded ends thereof firmly to the border-wire. By reason of the rounded formation of the ends of the stay or pressure-distributing element 11 the same has two points of contact with the under surface of the border-wire 8, as at 13 and 14 in Fig. 1. This stay or pressure-distributing element 11 is practically endless, the ends of the same meeting at a point within the frame 1 and coupled together by means of a suitable coupling member 15. In other words, the pressure-distributing element is in the form of a loop, the parallel sides thereof being closed by rounded or other shaped ends, and, if desired, this element 11 may be formed of a single piece of material.

The clips 12, alluded to above, are each provided at their ends with hooks 16 and an intermediate hook 17, the end hooks embracing the upper convolutions of the springs and also the corresponding side of the stay or pressure-distributing element, the intermediate hook 17 being bent upwardly between the inner edges of the said convolution and over the corresponding side of the stay or distributing element, as clearly shown in the drawings. It will be observed that the looped stay or pressure-distributing element has its sides arranged above corresponding pairs of transverse support-wires, or, in other words, that the sides of the said element 11 are arranged along corresponding upper edges of corresponding rows of springs above and in a manner similar to the arrangement described with reference to the transverse support-wires. The ends of the elements 11 which contact with the border-wire 10 are secured to the latter by means of the same form of clips as that designated by the reference character 12. However, it is to be understood that the form of clips at the ends of the elements 11 may differ in form from those associated with the said element and the springs and that these particular forms of clips may be the same in form as the clips described and associated with the support-wires and the lower convolutions of the springs. It is to be still further understood that these upper clips may be sprung or otherwise secured in any suitable manner to their corresponding elements. Furthermore, the bottom clips may be the same as the upper clips, or modifications may be made with reference to the clips.

In the construction of spring-cushion work for couches the ends of the border-wire need

not necessarily be even with the outer edge of the frame, as gathered from the construction illustrated by Figs. 1 and 2, for the reason that at the head end of the frame of the couch 5 springs are set in to continue the construction with the rise of the usual head of the couch. The foot of the couch is generally rounded over, so that ordinarily the only extension needed is on the sides. However, occasionally 10 a construction may be formed where the ends need to be even—that is to say, the outer edges of the ends of the border-wire should lie substantially over the outer edges of the wooden frame on said end, and in 15 order to do this a different stay-wire than the looped stay or pressure-distributing element hereinbefore described is employed. For instance, a peculiarly-bent stay or pressure-distributing element 18 is secured to the border-wire and the upper convolutions of the 20 springs in the manner clearly illustrated in Fig. 6. It is obvious, therefore, that in the construction of a cushion wherein the ends of the border-wire are substantially over the 25 outer faces of the ends of the wooden frame the form of stay or pressure-distributing element 18 should be employed and that when such an arrangement is provided the ends, as well as the sides, of the cushion are substantially 30 at a right-angle with respect to the top and bottom of the cushion, providing a substantially rectangular cushion. Of course the stay or pressure-distributing element 18 is disposed only at the end of the work, the 35 looped stays or pressure-distributing elements 11 being arranged intermediate the ends of the work. However, this pressure-distributing element 18 is bent in such manner as to form parallel side members for engagement upon opposite sides of the upper 40 convolutions of a series of alining springs.

My peculiar arrangement possesses all of the desirable features of a spring-cushion for beds, chairs, couches, and the like, and whenever 45 pressure is applied to the cushion the pressure upon the edge wire and the transverse stay-wires or other elements is directly upon the edge of the springs, and therefore there is absolutely no tendency of the springs 50 turning or tilting whenever pressure is brought to bear thereupon or upon the border, stay, or supporting wires. Another advantage derived is that when pressure is applied to any portion of the cushion it is distributed 55 over the portion of the cushion surrounding that upon which the pressure is directly applied, and therefore the farther the cushion is depressed the larger the area over

which the pressure is distributed, and consequently the greater will be the resistance of the cushion. A still further advantage resides in the fact that by reason of the peculiar connection of the clips with the corresponding elements the different elements are held in place against accidental displacement. A 60 still further advantage resides in the fact that I am enabled to employ double cone springs in a cushion without the employment of slats for the support of the springs, which latter is a rather expensive arrangement. Moreover, when the springs are mounted upon slats it is the custom to tie the springs together at their tops, all of which I eliminate. I gain an advantage, too, over the old method of supporting the springs 65 upon webbing, necessitating the tying of the springs at their tops, this old method being insecure. In other words, it has been demonstrated that I can use support-wires formed in such manner as to be driven or otherwise 70 secured in the framing of a couch, chair, bed, vehicle-seat frame, or the like and arrange the support-wires in such a manner as to support the springs against tilting movement and securing the latter to the other elements 75 associated with the structure in such manner as to provide an inexpensive construction. Furthermore, I am enabled to arrange a series of double cone springs within a framework and out of contact therewith and yet be 80 enabled to produce a structure wherein the same is perfectly rectangular in form:

I claim—

In a spring-cushion, the combination with a frame, of support-wires arranged in pairs 95 therein, springs mounted upon corresponding pairs of support-wires, means for securing the springs to the support-wires, a border-wire disposed above and in alinement with the outer edge of the aforesaid frame, and a 100 pressure-distributing element comprising a single piece of material, bent to form parallel side members for engagement with opposite sides of the tops of alining-springs, the ends of the said element being forced against the 105 under face of each side of the border-wire by said springs, and means engaging the said ends of said element and the sides of the border-wire to hold them together.

In testimony whereof I affix my signature 110 in presence of two witnesses.

WATSON R. SMITH.
